UNITED STATES PATENT OFFICE.

ALBERT M. BOWERS, OF NEWARK, NEW JERSEY.

LEATHER-WORKING MACHINE.

SPECIFICATION forming part of Letters Patent No. 392,004, dated October 30, 1888.

Application filed February 18, 1888. Serial No. 261,476. (No model.)

To all whom it may concern:

Be it known that I, ALBERT M. BOWERS, a citizen of the United States, residing at Newark, in the county of Essex and State of New Jersey, have invented certain new and useful Improvements in Leather-Working Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to that class of leather-working machines in which a bearing is adapted to engage one side of the leather and a staking-blade or other leather-working tool to engage the other side, the two working together backward and forward and coming in contact with the leather at the forward end of the stroke, then together moving backward in operative relation to the leather, then at the rear end of the stroke separating, so as to allow the leather to be changed in its position 20 between the jaws of the machine, and in the said separated relation moving forward to again come together to engage the leather and repeat the operative stroke.

25 The invention consists in the means herein-after specifically described, and finally embodied in the clauses of the claims.

Referring to the accompanying drawings, in which like letters of reference indicate corresponding parts in each of the several figures, 30 Figure 1 is a side elevation of a leather-working machine of the class to which my improvements belong. Fig. 2 is a front view of the improved bearing in detail. Fig. 3 is a view 35 of the same in its relation to the blade, and Fig. 4 is a side elevation of a modified blade or tool.

In said drawings, *a* indicates the frame of a leather-working machine; *b*, a vibrating beam 40 or rocker, which carries a bearing, *c*, to engage the upper side of the leather, being given a reciprocating movement by means of a connecting-rod, *d*, and wheel *e* in any suitable manner, the said wheel, connecting-rod, and 45 vibrating beam being in their construction, arrangement, and operation substantially the same as in a prior patent granted to me July

5, 1887, No. 365,963, the said connecting-rod *d* serving as a carriage for a series of levers, *f*, *f'*, *g*, *h*, *i*, and *j*. Upon the last of said levers 55 is arranged a staking-blade or blades, *k*, adapted to co-operate with the bearings *c* in giving finish to the leather. The said staking-blade *k*, under the influence of the wheel *e*, connecting-rod *d*, and levers, has a reciprocating movement with the bearing *c*, so that they move together in performing the operative stroke. In a cotemporaneous application I have shown the said bearing *c* to consist of a series of rollers or movable bearings, the same being peculiarly desirable under certain circumstances 60 to secure peculiar results upon the leather. In the present case, to secure other results upon the leather, I show the said bearing constructed of a series of cushions or pressure-bearings, *l* *m*, said bearings being rigidly secured to the head *b'*, which consists, preferably, of felt, leather, or other yielding material. Said leather or felt is held between clamping jaws or blocks *n* *o* *p*, which are suitably bolted 65 or otherwise held upon the head *b'* of the machine in any suitable manner, the peculiar mode preferred being shown in Fig. 3, in which the jaw or block *n* is bolted upon the head *b'* by means of the bolt *q*, the leather or felt bearing *l* being held against said jaw or block *n*, the bolt *q* passing through both the said blocks, head-piece *b'* and the set-screw *r* co-operating with the blocks *o* *n*, and the lower end of the bolt *q*, in clamping the bearing *l*, 70 as will be understood upon reference to Fig. 3. Upon the opposite side of the block *n* is another bearing, *m*. This is preferably of leather, doubled to present a rounded surface of smooth-grain leather to engage the grain side of the 75 leather being finished. The said doubled leather, *m*, is clamped against the block *n* by means of a plate, *p*, the latter being held against said bearing *m* by means of a bolt, *s*. The bearings *l* and *m* are disposed a little apart 80 from one another to allow the introduction of the staking-blade therebetween, so that a deep fold, crimp, or crease is formed in the leather as it is drawn through the machine. By having the bearings *l* and *m* rigidly secured to the head a greater frictional contact is secured, 85 which is specially effective in securing the desired results on firm and hard leather.

I may employ a single blade in lieu of the

double, as shown in Fig. 4, which enters between bearings *l* and *m*, and instead of having two rigid bearings, *l* and *m*, I may have but one, in that case the staking-blade being adapted to engage the side of the said stationary bearing. Other changes of construction may be made on the machine without departing from the spirit of this invention. Additional blades may be added to the series shown.

10 Having thus described the invention, what I claim as new is—

15 1. The combination, in a leather-working machine, of leather or other flexible bearings, *l* and *m*, and a staking-blade adapted to enter between said bearings and form a deep crease or fold in the leather, substantially as and for the purposes set forth.

20 2. In a leather-working machine, the combination of a frame, *a*, vibrating beam *b*, rod

d, wheel *e*, head *b'*, carrying stationary bearings *l* and *m*, and a lever, *j*, carried by the said head *d*, and actuated by a series of levers on said rod *d*, the said lever *j* having thereon a staking blade or blades *k*, substantially as set forth.

25 3. In combination with the head *b'*, a leather-working machine, clamping blocks or jaws *n*, *o*, *p*, and *q*, flexible bearings *l* *m*, rigidly secured to the head, suitable set-screws, and bolts, substantially as and for the purposes set forth.

In testimony that I claim the foregoing I have hereunto set my hand this 1st day of February, 1888.

ALBERT M. BOWERS.
